UNITED STATES PATENT OFFICE.

THOMAS ROBJOHN, OF NEW YORK, N. Y.

IMPROVEMENT IN FLUTED RUFFLES.

Specification forming part of Letters Patent No. 42,510, dated April 26, 1864.

To all whom it may concern:

Be it known that I, THOMAS ROBJOHN, of the city, county, and State of New York, have invented a new and useful Improvement in Fluted Ruffles; and I do hereby declare that the following is a full, clear, and exact description of the same, reference being had to the accompanying drawings, forming part of this specification.

In the manufacture of fluted ruffles and fluted or gauffered trimmings and fabrics generally it has been common to use for the purpose of retaining the flutes in place a thread, which, after having been coated with a solution of gum or other adhesive material, is placed in contact with the flutes and caused to adhere thereto. There is no objection to the use of this thread on white muslin goods, but in silk and colored goods the moisture which is in the said thread when it is first applied frequently produces a stain or discoloration.

My invention consists in the manufacture of fluted ruffles without the use of an adhesive thread by pressing down the flutes into a flat or plait-like form at any portion of the width of the ruffle with such a degree of pressure that the so pressed portion will retain its pressed form, and so retain the flutes in place.

Figures 1 and 2 are face views of two different kinds of ruffles manufactured according to my invention, the latter having been pressed flat in a central line and the former along one edge. Fig. 3 is a longitudinal section of the unflattened fluted portions of the ruffles. Fig. 4 is a longitudinal section of the flattened portion of the ruffle.

The pressing and flattening of the portion *a* of the ruffle may be effected by various means, but the best mode of doing it is by means of a presser operating between the

fluted rollers by which the fluting is performed, substantially as described in Reissued Letters Patent No. 1,556, and flattening the desired portion of the flutes by pressing them against the flat bottom of a circumferential recess formed in one of the rollers, or between the two rollers having the same axis, the said presser having either an intermittent or a constant pressure. The portion of the flutes thus flattened may be in a central line, or in a line at any distance from either edge, or at one edge, according to the style of ruffle desired, as the sewing by which the ruffle is attached to a garment or secured to or in a band should come through this portion. The pressed portion of the flutes has in the section lengthwise of the ruffle (represented in Fig. 4) the same appearance as what are called "box-plaits." The pressure applied must be sufficient to make the pressed portion retain this form, which will insure the retention of the flutes *b b* in proper form. The flattening operation of the presser will be aided by the heating of the fluting-rollers.

The ruffle may be made either single or two-ply. It may be taken from the fluting-machine, if required, to a sewing-machine, and then stitched or ornamented in a similar manner to the fluted goods made with adhesive thread.

Having now described my invention, I claim as a new article of manufacture—

A fluted ruffle in which the flutes are retained in place without the use of an adhesive thread by pressing them flat along any portion of the width of the ruffle, substantially as herein specified.

THOS. ROBJOHN.
